UNITED STATES PATENT OFFICE.

SIDNEY W. BRAINERD, OF CEDAR RAPIDS, AND LEE C. MANN AND THOMAS E. MANN, OF GLADBROOK, IOWA; SAID BRAINERD ASSIGNOR TO SAID LEE C. MANN AND THOMAS E. MANN.

BED AND CYLINDER PRINTING MACHINE.

SPECIFICATION forming part of Letters Patent No. 498,530, dated May 30, 1893.

Application filed July 27, 1891. Serial No. 400,832. (No model.)

To all whom it may concern:

Be it known that we, SIDNEY W. BRAINERD, residing at Cedar Rapids, in the county of Linn, and LEE C. MANN and THOMAS E. MANN, residing at Gladbrook, in the county of Tama, State of Iowa, citizens of the United States, have invented certain new and useful Improvements in Bed and Cylinder Printing Machines; and we do hereby declare the following to be a full, clear, and exact description of the invention, such as will enable others skilled in the art to which it appertains to make and use the same.

This invention relates to hand printing presses, and embodies various improvements in the construction of the style of press described in Letters Patent No. 355,407, issued to Thomas E. Mann on the 4th day of January, 1887.

The object of this invention, is, in general, to improve the construction of a printing-press having the essential characteristics of the press described in said Letters Patent, and with a view to the better adaptation of the press to the requirements of printing offices in many particulars, which will be hereinafter specifically referred to.

In the accompanying drawings, forming a part of this specification, Figure 1, Sheet 1, represents a partial side elevation of the simplest form of press embodying our invention; Fig. 2, a plan view of the same; Fig. 3, a partial end view of the bed-block at the end and its connected rail; Fig. 4, a fragmentary sectional elevation of the parts shown in Fig. 3, showing the construction of a device for adjusting the height of the rail at the outer end; Fig. 5, a central longitudinal section of the meeting ends of the middle and terminal rails and the connected iron parts; Fig. 6, a plan view of the same; Fig. 7, a central, longitudinal section of a portion of the track designed to relieve the edge of the type-form from the pressure of the cylinder. Fig. 8 is a side elevation of a modified form of the same; Fig. 9, a central, longitudinal section of the track at the middle, showing a device for elevating a portion thereof; Fig. 10, a sectional view of the timbers of the frame, showing the manner

of connecting them, and Fig. 11, a transverse section of the parts shown in Fig. 6, on the line of the center of the conical socket therein. Fig. 12, Sheet 2, is a side elevation of one end of the press, showing the arrangement of the cylinder and inking device; Fig. 13, a plan view of the ink disk and contiguous parts; Fig. 14, a plan view of the device for actuating the ink disk; Fig. 15 a front elevation of the step or bearing for the same; and Fig. 16, a detail of the bearing for the ends of the final ink-roller. Fig. 17, Sheet 3, is a side elevation of one end of the press, showing a modification in the construction of the inking device; Fig. 18, a plan view of the same; Fig. 19, a side elevation showing means for actuating the fountain-roller; Fig. 20, a plan view of the same, and Fig. 21, an end elevation of the terminal base block with the ink-trough attached. Fig. 22, Sheet 4, is a vertical section on the center line of the ink-disk, showing a modification in the mounting of the same; Fig. 23, a similar view of the paper-table and its supports, on the line of the middle of the supporting brackets, and Fig. 24 a plan view of the same as seen from the underside. Fig. 25, Sheet 5, is a central, longitudinal section of one end of the cylinder; Fig. 26, a plan view of the same, with the gripper attached; Fig. 27, an end view of the cylinder, with the head detached; and Fig. 28 a fragmentary sectional view of the cylinder on the line of the center of a plug therein.

Similar letter of reference indicate corresponding parts.

Referring now to the drawings, the supporting frame for the bed consists essentially of longitudinal beams A A resting on transverse beams A' A'. These are connected simply by dowel pins a'', so that the timbers may be easily and quickly connected and disconnected. The construction is such as to give a strong, stable floor support for the iron bed U on which the type-form is placed, while in moving it is very convenient, the parts being detached by simply lifting off the upper ones, and may then be handled separately.

On top of the beams A A rest the middle track-rails B B. These are separated at the

ends by transverse bars B'' B'' the rails being drawn tightly against the ends of the bars by rod-bolts B''' B''''. Upon the ends of these middle rails abut the ends of the terminal 5 rails B' B', the inner ends resting in gains in the transverse bars B'' B'', which rest on the bed-supporting frame, and the outer ends on terminal floor-block A'' A'', to which they are connected removably by dowels, as shown in 10 Fig. 3.

To each end of the rails B B is connected a casting D, the rail fitting inside the casting, as shown in Fig. 11. By reference to Fig. 5 it will be seen that the rails meet within this 15 casting, so that the side flanges thereof, together with the abutting cross-bars B'' B'' afford lateral bearings for both the middle and terminal rails. Into the socket so formed the inner ends of the terminal rails slip, being attached or detached in a moment, and being held securely on all sides when in position. The upper edges of the rails are all faced with band iron p p' p'', thus making a durable 20 track for the cylinder E mounted to roll thereon. At the proper place for the cylinder to rest at each terminus is a depression b'', which holds the cylinder until it is started down the incline of the track B' by the hand of the operator.

30 While in the act of printing, the cylinder bears heavily on the type, as will be understood. In presses of this character a common difficulty has been the tendency to cut the paper and batter the type at the edge of the 35 form as the cylinder rises upon it and leaves it. To obviate this we provide a slight elevation in the track as it approaches the edge of the form, the elevation extending to a point where the pressure of the cylinder will take 40 effect on the first line of type, but without having to climb in order to do so. This may be a shoulder d^x formed on the upper face of the casting D, as shown in Fig. 8, but is preferably formed on an adjustable plate, F, having a slot f therein, whereby it may be accurately adjusted along the rail B, and fixed in 45 place by a screw f''. A larger, sectional view of the same is shown in Fig. 7.

As the same trouble would be experienced 50 in the middle of the bed where the two forms meet, suitable provision is made at this point to the same end. This consists in means for elevating the band-iron face of the rail at this point. The device for that purpose is 55 illustrated in Fig. 9. In the band-iron is a hole, and in this hole is set the shouldered head of a screw or bolt p having a suitable nut p' set in a socket of the rail. By means of a screw-driver the screw may be turned 60 and the elevation of the track at the middle accurately adjusted.

A further improvement in the construction of the track is in the socket-plate d. This has a conical socket d' in its upper surface adapted 65 to engage with a corresponding conical spur on the tread of the cylinder. Inasmuch as the cylinder passes from end to end of the

track without gearing or like continuous connection with the track to keep it in relatively the same position respecting the type-form, it 70 is necessary to provide some means for righting any slight variations that the cylinder may make in moving back and forth, as set forth in the Letters Patent above referred to.

The improvement consists in the application 75 to the rail-castings D D of socket-plates d d''. One of these has lateral flanges fitting in corresponding inner grooves in the casting D, as in Fig. 11, and held in place by means of a set-screw d''. This admits of longitudinal 80 adjustment of the socket-plate as will be seen in Fig. 2. Opposite this plate on the other rail is a transversely adjustable socket-plate d fitting in a recess in the top of the casting D. This plate is provided with slots 85 d''' through which pass the holding screws, and by means of which the plate is adjusted sidewise. It will be noticed that the plates of the same kind are placed diagonally opposite each other on the track. This construction 90 and arrangement admit of a careful adjustment of the plates both longitudinally to suit the periphery of the cylinder, and laterally, to correspond with its length.

Provision has also been made for the vertical 95 adjustment of the outer ends of the rails B', to vary the incline thereof. Under the rail is placed a bolt a with a head adapted to support the rail, and provided with a nut a' seated in a socket or recess a'' in the floor-block A''. By turning the nut the rail may be raised or depressed at will, with the effect of correspondingly increasing or diminishing the speed with which the cylinder moves. This is specially useful, also, in truing up 105 the frame of the press on an uneven floor, and serves furthermore to compensate any unevenness in the weight of the cylinder at the respective ends thereof.

To the outer ends of the rails B' B' are connected uprights C' C' adapted to support the feed table C. The parts are strengthened and braced by the band-irons c c'. The former is secured to the rail and support on the back side, with a foot connecting with the 115 table. The other curves forward and connects with the table near the forward edge. This may be simply a continuation of the iron track, and its form is such as to support the table, serve as a bumper for the cylinder 120 at the end of its movement, and give symmetry to this part of the press.

In the figures of Sheet 2 are shown the details of a self-inking device. The heads of the cylinder E are provided with an axle E'', 125 and on this is loosely hung a pair of bails G G. To each corner of the bails are connected travelers g running on the track. Inside of these travelers, to the transverse portion G' of each bail, is attached a pair of 130 hangers g' g' carrying the inking roll h''. The upper portion of each hanger is screw-threaded, as shown in Fig. 16, and made adjustable vertically by means of suitable

jam-nuts, thus permitting a careful and nice adjustment of the roll with respect to the travelers g g .

Between the tracks at each end of the frame is mounted an ink-disk H , adapted to revolve in a suitable bearing or step I . This disk is set on an incline, as shown, the lower edge thereof being lower than the inking-roll at any point in its movement, and the upper edge projecting considerable higher than the track. As the cylinder moves to either end of its path the inking roll is carried up the face of the ink-disk, which being supplied with ink transmits it to the roller. This in turn inks the type first after the passage of the cylinder and again in advance of the cylinder as it returns, thus giving the customary double inking of the type.

Suitable provision is also made for turning the ink-disk. On a pivot k attached to the upright C' is hung an arm K , curved forward at the upper end, where it is provided with a small roll k'' and a weight, as of lead, k''' . To the other end of the arm is hinged a rod K' adapted to slip in a bearing k'''' attached to the rail B' . On this rod is pivoted a dog K'' , weighted at the lower end, and adapted to engage with the ratchet-teeth formed on the under-side of the disk. A collar k' limits the backward movement of the rod K' . The operation of this device is as follows: When the parts are in the position shown in the full outline in Fig. 12 the roll k'' rests on the rim of the cylinder, and the dog is thereby pushed forward and down the under face of the disk (the farther side). As soon as the cylinder moves away from that position the upper end of the arm K is liberated, while the pawl K'' engages with the ratchet. Now if the weight k''' be heavy enough, the upper end of the arm will at once fall, moving the disk under the roll h'' still resting upon it. In practice, however, the weight is not made sufficiently heavy for this, which would be injurious to the roll and detrimental to the proper distribution of the ink on the disk. But the instant the roll leaves the ink-disk, the weight of the upper portion of the arm K carries the pawl back, as indicated by the dotted lines, thereby turning the disk a limited distance. This distance may be regulated by moving and setting the collar k' . By providing the step I with slots i i the same may be vertically adjusted by the bolts i' i' , see Fig. 15.

The inking device just described is automatic so far as taking the ink from the disk and spreading it on the face of the type is concerned. On Sheet 3, however, is shown the detail of a device for automatically supplying the disk with ink.

To the upper end of the floor-block A''' is attached an ink-fountain J . In this is mounted the fountain roll h , in the usual manner, near which is the upper edge of the disk. On the disk is mounted an independent roll h' , with bearings extending from each end thereof. The backward portion of the hanger g'

terminates in a fork g'' adapted to catch the bearing at either end of this roller as the cylinder moves toward the end of its path, and thus push the roll to the upper edge of the disk and upon the fountain roller h . Having gathered a little ink on its surface thereby, it runs down the disk again by its own gravity as the cylinder moves away, transmitting the ink on its surface to the disk. In order to hold this intermediate roll from the possibility of moving endwise on the disk so as to get out of the path of the forks above referred to, the slotted guides L may be provided, in which the ends of the roll shaft move. The guide also serves as a stop for the roll in its descent. Slots l and l' permit inclined and vertical adjustment by means of bolts l'' l'' , so that the roll may be made to clear the disk entirely at the lower end of its movement and allow the disk to turn. It is to be understood that these guides might be dispensed with, leaving the roll free to follow its own course down the disk. This was the original intention, but it has been thought desirable to confine the roll to some extent, and the guides have therefore been added as a supplemental feature.

To keep the fountain roll supplied with ink from the trough, we provide means for automatically turning it. To its axle is secured a ratchet M , and on the swinging arm K is mounted a pawl N with a suitable spring n . By the oscillation of the arm the ratchet is automatically turned, imparting like movement to the roll.

To adjust the ink-trough and its roll vertically the flange of the trough may be provided with slots j j , through which pass fastening bolts j' j' .

In the figures of Sheet 4 are shown devices for changing the incline of the ink-disk and the position of the feed table. The former is illustrated in Fig. 22. In this case the step I' has a socket o' which permits the shaft H' of the disk to swing a limited distance. The upper portion of the shaft has a bearing in a hole o of the plate O . The plate is provided with a slot o''' , through which passes a bolt o'' , the head of which is secured to the block A'' by a plate P screwed thereto. Besides performing its own proper function in supplying ink to the roll, the disk serves in an important degree to retard the cylinder as it approaches the end of its track, and bring it gradually to a state of rest. This is due in large measure to the inclination of the disk, so that by changing the incline of the disk the resistance is varied. This incline of the disk also aids in the starting of the cylinder, owing to the weight of the roll and its connections traveling down it. It is to be noted, further that the automatic inking devices above described all serve as buffers to the cylinder, and tend to stop it at the end of its path without the sudden shock which might at times take place without them.

We provide for the adjustment and easy removal of the feed table C by making slots c''

in the brackets *c* and *c'*, and connecting the table thereto by thumb-screws *c''' c'''*.

In the figures of Sheet 5 are illustrated the details of the cylinder and grippers. The cylinder is composed of straight staves *E E*, grooved at the edges and connected by strips of hoop or band iron *e' e'*. The joint should also be closed with white lead, pine tar and resin, or other like substance to render the same water tight. For the same purpose the inside of the cylinder is coated with a pitch composed of tar and resin. Over the ends of the wooden cylinder thus made are fitted neatly the iron heads *E' E'*. These have an axle *E''*, to which is secured a hand-wheel *T* (shown in Fig. 1, Sheet 1). The heads also have an overlapping annular flange *E'''*, which is turned perfectly true inside and out with a suitable taper inside, the outer faces of said flanges forming the tread of the cylinder on the tracks before described. Each of the head-flanges is provided with the conoid *e*, the purpose of which has been already described. These heads are bolted on the ends of the cylinder by suitable rod-bolts *e'' e''*, and are leaded or pitched to make a water-tight joint in the same manner as the staves. Our object in making the cylinder tight is to prevent the escape of dust, when the cylinder is filled with a dry substance, or liquid, when filled with water or other liquid. The advantage of this construction will be apparent when it is understood that a cylinder filled with scrap-iron and the like ordinarily weighs as much as all the rest of the press combined. It is therefore desirable to so construct the cylinder as to admit of the purchaser filling it, and thus avoid paying first class freight on dead weight of comparatively inexpensive material. The difficulty is obviated by filling the cylinder with water, or sand, or both, when it reaches its destination. To this end, the side of the cylinder not covered by the tympan blanket is provided with one or more plugs *S*, large enough to admit the filling material. To opposite sides of the cylinder are connected the grippers *Q Q*. These consist of a shaft *Q*, preferably of square material, with bearings turned at the ends and mounted in boxes *t t*. At intervals the shaft is slotted or mortised, and in these mortises are fitted the gripper blades *q q*. At least one of these should extend some distance back of the shaft and bear under a contractile spring *s*, which thus tends to raise the points of the gripper blades. On the other side of the shaft is a button *R*, the lip *r* of which may be swung over the blade by the hand of the operator, and thus hold the gripper down upon the paper. On the release of this button the gripper of course flies up automatically and releases the paper.

Fig. 27 represents the relative position of the parts as the cylinder approaches the bed *B*. The blades *q* are adjustably secured to the shaft by set-screws *q'*. The length of

these blades, and their adjustment in the shaft renders it possible to adapt the cylinder to the printing of varying sizes of paper 70 without shifting the position of the boxes *t t*. Thus, supposing that in the position shown in the drawings, the grippers are adapted to hold an eight column paper, by extending the blades to their full limit it may be possible to print a six column paper, without disturbing the shaft bearings, the blanket, or any other parts of the cylinder or its covering. 75

Having thus described our invention, we claim— 80

1. In a printing-press, the combination with a type form of a track having a horizontal portion adjacent to the bed and inclined terminal portions leading thereto, the terminal portion of the track being relatively higher than 85 that portion of track conterminous with the type in the form, that is to say, the track being suddenly depressed between these termini of the type, whereby the cylinder descends gently upon the edge of the type form instead 90 of rising upon it, as described.

2. In a printing press, the combination with a type form and the tracks *B B' B'*, of the adjustable plate *F* adapted to be set opposite the edge of the type-form, the said plate having a shoulder on its upper face, and with the higher end joining the track *B'* and the other, the track *B*, whereby the cylinder is made to descend upon the type-form at the edge, as specified. 100

3. In a printing-press, the combination of the track *B B' B'*, the castings *D D*, adjustable sockets *d d d d*, and a cylinder provided with conoids *e e* to engage with said sockets.

4. In a printing-press, the combination with one or more type forms of the rail *B*, band iron *b* and adjusting screw *p p'*, substantially as and for the purpose set forth. 105

5. In a printing-press the combination of the detachable inclined rails *B'*, floor-block *A''* having mortise *a''* therein, the supporting bolt *a* and the nut *a'*, substantially as described. 110

6. In a printing-press, the combination of the bail *G*, suspended from the axle of the cylinder, travelers *g g*, adjustable hangers *g' g'* and ink-roll *h''*. 115

7. In a printing-press, the combination with a frame, bed and track substantially as described, of a cylinder having projecting axles 120 on the heads, a bail journaled thereon, an inking roll revolubly connected with the outer portion of said bail, and an ink-disk adapted to transmit ink to said roll said disk being inclined at an angle to the bed or track whereby the inking roll is caused to move upwardly and retard the movement of the cylinder as it nears the end of its path. 125

8. In a printing-press, the combination with a track and cylinder substantially as specified, of an ink-disk revolubly mounted at a point beyond the extreme travel of the cylinder, and provided with ratchet teeth, a pawl engaging with said teeth, a pivoted lever, over- 130

weighted at the upper end, which end lies in the path of the cylinder and is raised thereby, and a connection of the pawl with said lever, substantially as described.

5 9. In a printing-press, the combination with a cylinder and its track substantially as described, of the pivoted lever K having at the upper end the roller k'' and weight k''' , and at the lower end the gravity pawl K'' and a connection with the said lever, and the rotary ink-disk H having a ratchet engaging with said pawl.

10. In a printing-press, the combination with a cylinder and its track substantially as described, of an inclined ink-disk and means for adjusting the inclination thereof, and an ink-roll mounted on a bail connecting with the axles of said cylinder, whereby the retardation of the cylinder at the end of its travel 20 and the acceleration of the same at the beginning by the ink-roller may be varied as desired.

11. The combination in a printing-press of the ink-disk H having the spindle H', the step I' having socket o', the plate O having bearing o and slot o'', and means for fastening the same to the floor-block A''.

12. In a printing-press, the combination of an inclined ink disk, an ink-trough or fountain mounted near the upper edge thereof with a roll therein, an independent roll mounted to travel by its own gravity down the disk, and a pair of reciprocating forks adapted to catch the axles of said independent roll and 35 carry the roll up the disk into and contact with the roll in the fountain, as impelled by suitable actuating means.

13. In a printing-press, the combination of an inclined ink-disk, a primary ink-roll and 40 fountain mounted near its upper edge, an independent roll mounted on and adapted to

travel down said disk by its own gravity, means substantially as described for intermittently carrying said roll up said disk and into contact with the primary roll, and guides 45 for the axles of said independent roll.

14. In a printing-press, the combination with a revoluble inclined ink-disk, an independent ink-roll adapted to travel down the disk by its own gravity and having projecting axles, and guides for said axles, substantially as described, and with means for adjusting the inclination of said guides with respect to the disk, whereby the roll may be made to clear the disk entirely at some portion of its descent to permit the disk to turn. 50

15. The combination in a printing-press, of a cylinder and its track substantially as described, a bail journaled to the axle of the cylinder, an ink-roll journaled to said bail, a 60 pair of forks extending beyond said roller and adapted to engage with the axles of another roll, an inclined ink-disk, a loose roll adapted to travel down the disk by its own gravity, and having axles adapted to engage with the 65 said forks, and a fountain roll mounted in a trough or fountain near the upper edge of the disk and in the path of the independent roll.

In testimony whereof we affix our signatures in presence of two witnesses.
